HEAT-TREATING FURNACE

Elmer K. Hansen, Edgewood, Pa., assignor to
Westinghouse Electric Corporation, East Pitts-
burgh, Pa., a corporation of Pennsylvania

Application June 7, 1941, Serial No. 397,007

3 Claims. (Cl. 266—4)

My invention relates to heat-treating furnaces, and more particularly relates to heat-treating furnaces for heat-treating, in a short heat-treating cycle, a large charge or batch comprising a plurality of spaced, suspended, metallic sheets, the heat-treating including heating and then quenching the charge.

It is an object of my invention to provide a heat-treating furnace comprising a closed heating-chamber and a quenching means under the heating-chamber, the furnace being so constructed that a charge to be heat-treated therein is first moved between the heating-chamber and the quenching means, then raised by suitable charge-moving means into the heating-chamber for heating, and after heating dropped quickly into the quenching means below the heating-chamber in such manner that the interval of time during which the charge is in transit between the heating-chamber and the quenching means is minimized.

It is a primary object of my invention to provide a heat-treating furnace having a wall-structure defining a heating-chamber with a charging-opening at the bottom, and a quenching means under the heating-chamber, the quenching means being sufficiently below the heating-chamber to allow a supporting means to be interposed between them for receiving a loaded charge-rack from which the charge of suspended plates or sheets is supported, the charge-rack being movable on the supporting means from a position between the heating-chamber and the quenching means to a position laterally away therefrom so that the charge-rack can be conveniently loaded or unloaded.

In the form of my invention which is at present preferred, the charge-rack, from which the metallic sheets are suspended, is slidable on the supporting means. The charge-rack and the supporting means are provided with cooperating rail and roller devices permitting the charge-rack to be easily moved to and from a position underneath the charging-opening of the heating-chamber, the cooperating devices maintaining the charge-rack aligned on its supporting means so that the supporting means also serves as a guiding means for guiding the charge-rack during its movements.

A feature of my invention resides in providing the supporting means for the charge-rack with a section underneath the heating-chamber, which is easily movable out of the path of a charge moving between the heating-chamber and the quenching means.

Another feature of this preferred furnace comprises a suitable closure means for the bottom charging-opening of the heating-chamber, the closure means comprising a closure which can be novelly rolled between closing and opening position for the charging-opening, the rolling motion of the closure as it approaches or leaves the charging-opening including combined relatively vertical and horizontal directional components, with the vertical components being relatively larger when the closure is nearer the charging-opening and becoming progressively relatively smaller as the closure moves away from the charging-opening and the horizontal components being relatively smaller when the closure is nearer the charging-opening and becoming gradually larger as the closure moves away from the charging-opening, until finally the closure moves substantially laterally only when it is below the charging-opening and clear of the wall-structure.

It is another object of my invention to provide a means for suspending a sheet to be heat-treated, the means securely locking the sheet at its upper edge.

Many objects, features, innovations and advantages of my invention, in addition to those mentioned above, will be apparent from the following description thereof which is to be taken in conjunction with the accompanying drawings. In these drawings, which are on considerably varying scales,

Figure 1 is a lengthwise vertical view, partly in section and partly in elevation, of a heat-treating furnace embodying the teachings of my invention, this figure being taken substantially along the line I—I of Fig. 2;

Fig. 2 is a transverse vertical sectional view of the furnace, taken substantially along the line II—II of Fig. 1;

Fig. 3 is a horizontal sectional view of the furnace, taken substantially along the line III—III of Fig. 2;

Fig. 4 is an elevational view, with a small part shown in vertical section, of a closure for the bottom charging-opening of the furnace;

Fig. 5 is a vertical sectional view, transverse to the view of Fig. 4, of the closure;

Fig. 6 is a plan view of one of the sets of rail means on which the closure is moved to and from closing position for the charging-opening;

Fig. 7 and Fig. 8 are an elevational view and an end view, respectively, of this set of the rail means.

Fig. 9 is a plan view of a charge-rack from

which the metallic sheets are suspendingly supported;

Figs. 10 and 11 are a lengthwise sectional view and a transverse sectional view, respectively, of the charge-rack from which the metallic sheets are suspended in spaced substantially parallel relation;

Fig. 12 is a detail view of a rack-hook engaging a hoist-hook of a hoisting means for raising and lowering the charge-rack;

Fig. 13 is an elevational view of one of a plurality of special bars for suspendingly supporting a metallic sheet from the charge-rack;

Fig. 14 is a fragmentary detail view, in elevation, showing the manner in which a sheet is suspendingly secured by the bar of Fig. 13;

Fig. 15 is a transverse elevational view of the detail of Fig. 14; and

Figs. 16, 17 and 18 are, respectively, a plan view and elevational views in planes at right angles to each other, of a wedging pin for securing a metallic sheet in the slot of the bar of Fig. 13.

The furnace which is herein described is particularly useful for the heat-treating of metallic sheets comprising aluminium or aluminium alloys, and particularly sheets having pure aluminium protective coatings. In the heat-treatment of such aluminium sheets, time is an all important element in the heat-treating process, and my preferred form of furnace herein described is built so that the sheets can be heated in as short a time as possible in order to prevent the diffusion of alloying elements of the inner core of the sheet out into the outside coating of the sheet, and to permit quenching in as short a time as possible, a few seconds at the most, after the sheets have been suitably heated.

Referring more particularly to the drawings, and in particular to Figs. 1, 2 and 3, in which smaller details are either omitted or shown somewhat schematically because of the scale of the drawings, the furnace consists of a wall-structure, indicated in its entirety by the reference numeral 1, comprising side walls 2 and 4, end walls 6 and 8, and a top wall 10, defining a heating-chamber 12. The wall-structure 1 is built of any suitable refractory and insulating brick, and is encased in a gas-impervious metallic outer shell 14. The wall-structure 1 is supported by a suitable structural framework, indicated in its entirety by the reference numeral 16, at a considerable distance above a quenching means 18 which can be disposed in a floor or foundation 20 in which the structural framework 16 may be secured.

The structural framework 16 comprises structural I-beams 22 at one end of the furnace and I-beams 23 at the other end of the furnace, the I-beams 22 being spaced from the I-beams 23 to provide an unobstructed space along the length of the furnace for receiving a charge to be heat-treated in the furnace, which is loaded into the heating-chamber 12 through a bottom charging-opening 24 closed by a closure indicated in its entirety by the reference numeral 26.

The closure 26, which will be described in somewhat greater detail later, includes a plurality of wheels rideable on rails at the ends of the furnace, two sets of rails 28 and 30, respectively, being provided.

The sheets to be heat-treated in the furnace are supported by a charge-rack 31 which is shown in Figs. 9, 10 and 11, the charge-rack being rideable on a supporting means comprising a track

having an elevated roller track-rail 32 along one end of the furnace and a second elevated roller track-rail 34 along the other end of the furnace.

The elevated track-rails 32 and 34 are each provided with a movable rail-section 36 having a length which is somewhat greater than the short dimension of the heating chamber 12, the heating chamber being preferably rectangular. Each of the rail-sections 36 has one end pivoted at 38 so that both sections 36 of the track-rails 32 and 34 can be dropped into vertical position, the other ends of the rail-sections 36 being provided with any suitable means whereby they can be locked or latched in raised position in alignment with the stationary parts of the elevated track-rails 32 and 34. The stationary parts of the track-rails 32 and 34 extend beyond both sides of the furnace so that a charge-rack can be easily accommodated on each side of the furnace away from underneath the heating-chamber, enabling a second charge-rack to be loaded with sheets while a loaded charge-rack is undergoing heat-treatment.

The closure means 26 is moved to and from closing position by any suitable closure-operating means which, in this embodiment, comprises a pair of suitably-controlled pneumatic cylinders 40 at the ends of the closure means, the pneumatic cylinders being pivotally supported as at 44, and of such type as to keep the closure 26 at the extremity of its movements. The piston rods of the cylinders are pivotally connected to clevises 46 on the closure 26.

In order to raise a loaded charge-rack which is supported on the rail-sections 36, a charge-moving means is provided comprising a hoisting means having its operating mechanism on the top of the wall-structure 1. The hoisting means includes a reversible motor 52 suitably geared to drive a cable drum 54 around which are wrapped two pairs of cable chains. The cable drum 54 winds and unwinds a pair of spaced cable chains 60 passing over a chain guide-drum 62 at one end of the furnace, and winds and unwinds a pair of similarly spaced cable chains 64 passing over a chain guide-drum 65 at the other end of the furnace. Each of the cable chains passes through suitable hollow corner tubes fixed in the top wall of the furnace, and terminates in a hoist-hook 66 for engaging an associated rack-hook 68 secured to the charge-rack, so that the hoisting means can suitably raise and lower the charge-rack without significant swaying of the loaded charge-rack. The cable chains are provided with short solid tubes somewhat loosely fitting the fixed tubes in the top wall when the charge-rack is in raised position, so that air leakage is limited.

For the operation of the elements of the furnace thus far described a loaded charge-rack may be assumed to be on one of the stationary sections of the supporting means comprising the elevated track-rails 32 and 34. For heat-treating sheets suspendingly supported from this charge-rack, the rack is moved to a position on the movable rail-sections 36, which are underneath the heating-chamber 12. By controlling the pneumatic cylinders 40, the closure means 26 can be moved to a position on the substantially horizontal portions 10 of the rail sets 28 and 30, thereby uncovering the charging-opening 24. The cable chains of the hoisting means can then be lowered and the hoist-hooks 66 made to engage the rack-hooks 68 so that the charge-rack and the metal sheet charge thereon, under the charging-opening 24, can be raised into the heat-

ing-chamber 12, after which the closure 26 can be moved to closing position for closing the charging-opening 24. In the heating-chamber 12, the charge is heated by means of electrical heating means 74, or other suitable heating means, mounted on the side and end walls of the wall-structure 1.

Since aluminium alloy heating sheets are preferably heat-treated by heating to a relatively low temperature, say in the neighborhood of 950° F., it is desirable to provide convection heating in the heating-chamber 12. To this end suitable baffles 76, at the sides of the furnace, and baffles 78, at the ends of the furnace, terminate short of the top and bottom of the heating-chamber 12 so that air-recirculating paths are provided which may be downwardly between the baffles and upwardly between the baffles and the side and end walls 2, 4, 6 and 8, of the heating-chamber, where the circulating air is heated by the heating means 74. The air may be recirculated by fans 80 secured to shafts 82 extending through the top wall 10 of the wall-structure 1, and driven, through suitable belting, by motors 84. The shafts 82 may be supported in any suitable bearings and provided with packing glands to limit leakage of atmosphere. An apertured top baffle means 86 is provided across the tops of the baffles 76 and 78 for guiding the air flow along the top of the heating-chamber, the top baffle means 86 being provided with short cylindrical tubes 88 in which the fans 80 are disposed for substantially rectilinearly blowing the air downward through the suspended metal sheets carried by the charge-rack, the charge-rack comprising a substantially open framework to permit the air to pass freely between the sheets.

While a loaded-rack is being heated, the movable rail-sections 36 of the elevated track-rails 32 and 34 can be lowered so that the loaded-rack, after heating, can be lowered without interference. After the loaded charge-rack has been heated for the proper time, the closure 26 is moved quickly to open position, and at the same time the heating means 74 and the fans 80 are deenergized, and the hoisting means operated to lower the loaded charge-rack into the quenching-liquid of the quenching means 20 at a high rate of speed. In an actual embodiment of the furnace described, only about seven seconds are consumed from the moment the closure 26 starts to open until the loaded charge-rack is completely immersed in the quenching-liquid within the quenching means. After the loaded charge-rack has been quenched it is raised to clear the elevated rail-tracks 32 and 34 so that the movable rail-sections 36 can be moved back into alignment with the stationary sections of the elevated track-rails 32 and 34. The loaded charge-rack is then lowered so that the charge-rack rests on the elevated track-rails 32 and 34, on which it is moved to one side for unloading. After the heat-treated loaded charge-rack has been moved to one side on the track-rails 32 and 34, a second loaded charge-rack on the other side of the track-rails 32 and 34, which has in the meantime been prepared, may be moved to proper position under the charging-opening 24 for loading into the heating-chamber 12, and the heat-treating process repeated for this rack while the heat-treated sheets carried by the other rack are removed and new sheets, which are to be heat-treated, are suspended therefrom.

The rail-sets 28 and 30 are spaced apart a distance along the length of the furnace sufficient

5 to avoid interfering with vertical movements of the loaded charge-racks; and are above the track-rails 32 and 34 a distance sufficient to clear a charge-rack on the track-rails. In order to limit the time for loading and unloading the furnace it is desirable to move the closure 26 laterally of the length of the furnace, which is the shortest dimension of the charging-opening; and in one particular furnace, the width of the charging-opening was between $\frac{1}{2}$ to $\frac{1}{4}$ of its length.

10 If the furnace is of relatively large size for heat-treating large batches at one time, the closure means also becomes large and long and since the rails upon which the closure rides are at the ends of the furnace, it is desirable to provide means which will confine the closure movements to predetermined tolerances so that the closure will properly seat with respect to the wall-structure 1, for closing the charging-opening 24. Such means is especially desirable if gas-sealing means 15 are to be provided between the wall-structure 1 and the closure. To this end, the closure and the closure-supporting means, comprising the rail-sets 28 and 30, are provided with means for guiding the closure and for causing the closure to seat properly in the charging-opening 24 of the furnace.

20 With reference also to Figs. 4 and 5, the closure means 26 comprises a bottom gas-impermeable base plate 90 supported on a closure framework indicated in its entirety by the reference numeral 92. The base plate 90 is provided with an outer upwardly extending rib 94 substantially paralleling the edges of the base plate. Suitable refractory brick work 96, shaped to conform to the charging-opening 24, is supported and interlocked with the base plate 90. The rib 94 cooperates with a second parallel rib 98 to form part of a gas-sealing means 100 shown 25 and claimed more particularly in the joint application of P. G. Lessman and A. Krauscope, Serial No. 396,996, filed concurrently herewith and assigned to Westinghouse Electric & Manufacturing Company. This joint application has become Patent No. 2,354,127, dated July 18, 1944. The gas-sealing means generally comprises an inverted U-shaped set of members 102 slidable between the flanges 94 and 98 and spring-pressed 30 upwardly so that in closing position of the closure the inverted U-shaped members press against a bottom door frame 104 along the bottom of the vertical walls 2, 4, 6 and 8 of the wall-structure 1, the door frame 104 being protected against heat within the heating-chamber 12 by the refractory bricks of the wall-structure, which extend beyond the inner edges of the door frame.

35 The bottom side of the closure is provided with a pair of forward or leading flanged wheels 110 and 112 at the corners of the forward side of the closure, considering the forward side as that side closest to the wall structure 1 when the closure starts to move from open position to closing position. A second pair of rear, flanged wheels 114 and 116 is provided at the corners of the rear side of the closure; the gauge of, or the distance separating, the wheels 114 and 116 being less than that of the wheels 110 and 112. The wheels are journaled in any suitable manner by any suitable means secured to the closure framework 92. The front wheels 110 and 112 ride on inside rails 118 and 120, respectively, of the rail-sets 28 and 30, and the rear wheels 114 and 116 ride on outside rails 122 and 124, respectively. The rails are shaped so that the closure means, 40 in moving from opening to closing position, is

moved initially horizontal and during its final movement is raised so that the refractory portion 96 of the closure enters the charging-opening 24, and the gas-sealing means 100 engages the door frame 104. To this end the extremities of the rail-sets 28 and 30 are curved upwardly as shown in Fig. 7.

The inner rails and the outer rails of both rail-sets 28 and 30 are designed so that the front and rear sides of the closure are raised in the same direction at the same time thereby maintaining the closure substantially horizontal.

In order to keep the closure means properly aligned at all times during its movement so that it will suitably mate the wall-structure 1 about its charging-opening 24, the rail-sets 28 and 30 are provided with a gear rail 126 and a gear rail 128, respectively, in the form of a rack bar shaped to correspond to the associated rails 118 and 120, the gear rails 126 and 128 being provided with gear teeth. A gear 130 meshes with the gear rail 126 and a gear 132 meshes with the gear rail 128, the two gears being secured to a common shaft 134 rotatably supported by the closure framework 92. The gears 130 and 132 are in mesh with the gear rails 126 and 128 in all positions of the closure 26.

During movement of the closure 26, the meshing of the gears 130 and 132 with the gear tracks 126 and 128, causes both ends of the closure to move in the same direction at the same speed. If the closure is properly positioned initially, the gearing between the closure and the closure-supporting means, including the gear rails 126 and 128, will maintain the alignment of the closure.

The charge-rack 31 and its appurtenances for suspendingly supporting the metallic sheets to be heat-treated, are shown in greater detail in Figs. 9 through 18. The charge-rack comprises an open rack-frame 140 which is rectangular in shape and fits within the baffle structure of the heating-chamber 12. The rack-frame 140 comprises opposite long, frame sides 142 and 144, and also frame ends 146 and 148, the sides and ends being of suitable structural forms, to provide the necessary strength of the rack-frame. Secured to the frame ends 146 and 148, are guide rails 150 and 152, which ride on the supporting means comprising the elevated roller track-rails 32 and 34. Each guide rail extends for the full length of an end of the rack-frame and has down turned flanges 154 and 156 to confine the guide rails on the elevated roller track-rails 32 and 34.

Each of the frame sides 142 and 144, and each of the frame ends 146 and 148, is provided with a horizontal inwardly-extending leg 157 terminating in an upstanding leg 158 to form a channel. Somewhat inward of the frame end 146, the edges of the upstanding legs 158 of the frame sides 142 and 144, slidably support a cross-bar 159 which comprises an angle bar 160, between the frame sides 142 and 144, and metal supporters 161 secured, as by welding, to the ends of the angle bar 160. The end supporters 161 rest on the edges of the upstanding legs 158 of the frame sides 142 and 144, and are each provided with a down-turned lug 162 disposed within the channel of the associated frame side, so that the cross-bar 159, although slidably supported by the frame sides 142 and 144, is interlocked with the frame-sides. The angle bar 160 has a depending leg 163 provided with a plurality of spaced holes 164.

A plurality of other cross-bars 165, each of which is similar to the cross-bar 159 are slidably supported by the frame sides 142 and 144 at a spaced interval along the length of the rack-frame. Each cross-bar 165 has a depending leg 166, similar to the leg 163 of the cross-bar 159, the legs 166 also having space holes 164.

The holes 164 in the different legs of the slidably-supported cross-bars receive wires 168 which also pass through holes 170 in the upper part of a slotted clip bar 172, each wire being looped and the loop twisted for flexibly suspending the associated slotted bar 172. The wires and slotted bars form a suspending means for supporting metallic sheets from the framework 140 of the charge-rack 31.

Each slotted bar 172 also has a lever slot 174 in which a sheet can be inserted edgewise, Figs. 14 and 15 showing a part of a sheet S within a slot 174. An offcenter hole 176 is provided intermediate the ends of the slot for receiving a securing means for securing the sheet in the slot 174. Consequently, a side 178 of the slot 174 may be considered to have an enlarged indentation forming the major part of the hole 176, and the other side 180 of the slot may be considered as having a smaller indentation 182 or may be smooth if the hole 176 is sufficiently off center with respect to the slot 174. The bar 172 is somewhat resilient so that the sides of the slot are spreadable under pressure and can be maintained spread under pressure, the bar resisting this pressure and tending to force the slot sides back to normal position.

For securing a metallic sheet in place its edge is placed within the slots of a plurality of spaced bars 172 which are suitably aligned to receive the edge of the sheet, and a securing means comprising a securing pin or wedge 190, of special shape, is forced or driven into each hole 176 thereby wedging or pressing the sheet S against the slot sides corresponding to a slot side 180 so that the sheet is frictionally held in place. The number of bars 172 used to support a single sheet will, of course, depend upon the length of the edge of the sheet to be fastened.

A securing pin 190 is more particularly shown in Figs. 16, 17 and 18 and comprises a round rod of slightly less diameter than the holes 176. The pin is formed with right angular sides 192 and 194, the side 194, which may have a rounded tip, being adapted to be inserted in a hole 176 and the side 192 providing a convenient means by which the pin is inserted or withdrawn. The pin-side 194 is tapered to provide an end easily insertable in a hole 176, the taper having a surface 196 starting at about the vertical diameter of an end of the pin-side 194 which diameter is parallel to the pin-side 192, and terminating near the pin-side 192, as shown in Figs. 16 and 17. The taper surface 196 is provided with a small central ridge 198 for better forcing the sheet S against the slot side 180. In cases where the slot side 180 is provided with a small indentation 182, the ridge 198 may force the metal of the sheet S into this indentation so that the sheet is somewhat locked to the bar 172. The cross-bars 159 and 165 can be slid on the frame sides 142 and 144 to correspond to the length of the metal sheets to be heat-treated, and more than one sheet can be supported in substantially a single plane.

The charge-rack 31 is further provided with spaced cross members 200 to which the rack-hooks 68 are secured in spaced relation, the

charge-rack of the preferred embodiment having four such rack-hooks, one near each corner thereof. Each pair of associated rack-hooks 68 on a cross member 200 has secured thereto and between them an angle bar 202 having a relatively wide horizontal leg 204. A small retaining bar 206 is secured near the lower free edge of the leg 204. Each pair of the hoist-hooks 66, which is associated with a pair of rack-hooks 68 on a cross member 200, is similarly rigidly interconnected by an angle member 208 (Fig. 12) also provided with a retaining bar 210 near its upper free edge. The two retaining bars 206 and 210 provide an interlocking means which prevents the hoist-hooks from slipping from the rack-hooks, and, with the angle member 202 and 208, assure a substantial connection between the hoisting means and the charge-rack for substantially vertically raising and lowering the charge-rack in a manner to maintain the charge-rack substantially horizontal.

While I have described my invention in a form which is the preferred embodiment thereof, it is obvious that many modifications may be made thereof and equivalent elements substituted therein.

I claim as my invention:

1. A heat-treating furnace comprising a heating-chamber having a charging-opening, a movable closure for said charging-opening, furnace loading and unloading means comprising a charge-rack having means for suspendedly supporting a charge comprising a plurality of spaced suspended metallic objects, rail means for movably supporting said charge-rack so that a loaded charge-rack can be moved to a position in substantially vertical alignment with said charging-opening, said rail means including a section directly below said charging-opening, quenching means below said section of said rail means, charge-moving means for lowering a loaded charge-rack from said heating-chamber into said quenching means, and means for pivotally supporting an end of said section of said rail means so that said section can be swung to a position in which it will be out of the path of a loaded charge-rack being lowered into said quenching means.

2. A heat-treating furnace comprising a wall-structure defining a heating-chamber having a bottom charging-opening, a rack means comprising a substantially rectangular framework and a plurality of members secured to said framework, said members having rack-hooks above said framework, a rack-bar secured across a pair of said rack-hooks, said rack means having charge-supporting means comprising spaced depending bars for suspendedly supporting metallic objects, spaced rails below said charging-opening, on which said rack means is supported to be movable to or away from a position under said charging-opening, hoisting means comprising a plurality of cables passing through an upper section of said wall-structure, and terminating in hoist-hooks, and a hoist-bar across a pair of said hoist-hooks, said hoist-bar and said rack-bar providing interlocking means for preventing said rack-hooks from slipping from said hoist-hooks, said spaced rails being spaced apart a distance sufficient to permit said suspended sheets to be raised between them, said rails also having a movable section movable out of rail alignment for permitting said hoisting means to lower said rack means and the charge thereon, below said spaced rails.

3. A heat-treating furnace comprising a heating-chamber having a bottom charging-opening, 30 a quenching means under said heating-chamber, supporting means comprising a rail means between said heating-chamber and said quenching means for supporting, above said quenching means, a charge to be moved into said heating-chamber, means for moving the charge from said supporting means into said heating-chamber, and for dropping the charge from said heating-chamber into said quenching means, said rail means comprising a pivoted section, said pivoted section being placeable under said heating-chamber for supporting a charge directly below said heating-chamber, and movable out of the path of a charge being dropped from said heating-chamber into said quenching means.

ELMER K. HANSEN.
